DAVID H. WATTS, OF PHILADELPHIA, PENNSYLVANIA.

DESIGN FOR A TILE.

SPECIFICATION forming part of Design No. 19,441, dated November 19, 1889.

Application filed August 29, 1889. Serial No. 322,367. Term of patent 7 years.

To all whom it may concern:

Be it known that I, DAVID H. WATTS, a citizen of the United States, and a resident of Philadelphia, Pennsylvania, have invented a new and original Design for a Tile, of which the following is a specification.

My design for a tile is fully illustrated in the accompanying drawing, the view of which is a face view of the tile. The tile is quadrangular in shape, and at each corner is a foliated scroll in the form of a leaf, the stem of each scroll terminating at the corner. The edge of the tile is beveled.

I claim—

The herein-described design for a tile, substantially as described, and shown in the accompanying drawing.

In testimony whereof I have signed my name to this specification in the presence of two subscribing witnesses.

DAVID H. WATTS.
